UNITED STATES PATENT OFFICE.

WILLIAM ALLEN PENDRY, OF DETROIT, MICHIGAN.

DESIGN FOR A GRINDING-WHEEL.

SPECIFICATION forming part of Design No. 30,283, dated February 28, 1899.

Application filed January 21, 1899. Serial No. 702,993. Term of patent 7 years.

To all whom it may concern:

Be it known that I, WILLIAM ALLEN PENDRY, a citizen of the United States, residing at Detroit, county of Wayne, State of Michigan, have invented and produced a new and original Design for a Grinding-Wheel, of which the following is a specification, reference being had to the accompanying drawings, which form a part of this specification.

10 Figure 1 of the drawings is an enlarged plan view of a grinding-wheel, showing my new design. Fig. 2 is a view from one end thereof. Fig. 3 is a view from the opposite end of the same.

15 As shown in the drawings, the leading or material features of my design consist of a grinding-wheel A, of cylindrical form, of greater diameter intermediate the ends than toward the ends thereof, the longitudinal outline of the wheel narrowing from near the longitudinal center thereof toward the extremities thereof, said outline narrowing more toward one extremity than toward the opposite extremity, the outline at one end thereof 20 being thus longitudinally reduced toward the longitudinal center of the wheel more than the longitudinal outline of the opposite end of the wheel, the longitudinal outline of one end of the wheel (indicated at A') being curved 25 or hollowed from a point intermediate the ends of the wheel, as from the point a' to the

point a. From said intermediate point a' the longitudinal outline of the wheel is shown cut away or reduced toward the opposite extremity, as indicated on the line from a' to 35 a², leaving a grinding end of the wheel, as the end A', extending from the point a' to the point a of enlarged outline over that of the opposite or non-grinding end of the wheel A², as indicated on the line from a' to a², or, in 40 other words, the longitudinal outline of the end A² being so reduced that the end A' of the wheel has its periphery of narrower diameter at all points in cross-section than cross-sections at equal points from the center on 45 the end A' of the wheel.

It is apparent that a grinding-wheel of this design has the outline from the longitudinal center on the non-grinding end thereof reduced from the corresponding outline of the 50 opposite end or grinding-surface of the wheel.

Having described my invention, what I claim as new, and desire to secure by Letters Patent, is—

The design for a grinding-wheel, as herein 55 shown and described.

In testimony whereof I sign this specification in the presence of two witnesses.

WILLIAM ALLEN PENDRY.
